(57) **CLAIM**

The ornamental design for a device case, as shown and described.

DESCRIPTION

FIG. 1 is a front, left perspective view of a device case.

FIG. 2 is a bottom, rear perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof.

FIG. 8 is a rear view thereof.

FIG. 9 is a front, left perspective view of the device case shown in an open configuration.

FIG. 10 is a bottom, rear perspective view thereof.

FIG. 11 is a top view thereof.

FIG. 12 is a bottom view thereof.

FIG. 13 is a left side view thereof.

FIG. 14 is a right side view thereof.

FIG. 15 is a front view thereof.

FIG. 16 is a rear view thereof.

FIG. 17 is a front, left perspective view depicting a first disclaimed context.

FIG. 18 is a bottom, rear perspective view thereof.

FIG. 19 is a top view thereof.

FIG. 20 is a bottom view thereof.

FIG. 21 is a left side view thereof.

FIG. 22 is a right side view thereof.

FIG. 23 is a front view thereof.

FIG. 24 is a rear view thereof.

FIG. 25 is a front, left perspective view depicting a second disclaimed context; and,

FIG. 26 is a bottom, rear perspective view thereof.

Within the drawings, the broken lines show unclaimed portions of the device case, and form no part of the claimed design.

1 Claim, 21 Drawing Sheets
